UNITED STATES PATENT OFFICE

2,240,501

CUP MACHINE

Harold Greenhill, Chicago, Ill., assignor to Dixie-Vortex Company, Chicago, Ill., a corporation of Delaware.

Application April 5, 1937, Serial No. 135,138

8 Claims. (Cl. 93—36.2)

This invention relates to container or cup making machines, and particularly to a machine for making or forming cups from a flexible material such, for example, as a suitably treated water-proofed paper or flexible fiber board.

One object of the present invention is to provide a continuously operating rotary machine wherein suitably shaped blanks having an adhesive applied thereto are presented successively to a cup forming mandrel having novel means associated therewith for securing a cup blank thereto during the forming of a cup thereon, and having novel means incorporated in the construction of the mandrel for discharging a finished cup therefrom.

Another object of the invention is to provide a novel construction and arrangement whereby a presser roll is moved into operative relationship with the mandrel to engage a blank thereon during the forming of a cup, and is moved out of relationship with the mandrel to permit a finished or completed cup to be discharged therefrom.

Another object of the invention is to provide a machine capable of high speed operation wherein the cup material is introduced and fed to the machine in the form of an elongated relatively narrow strip from which the cup blanks are successively cut and presented to the forming mandrel and presser roll to be engaged thereby.

Another object of the invention is to provide a novel construction and arrangement whereby the strip of cup material is supplied with an adhesive at spaced intervals adjacent one of its edge portions and thereafter cut across between the spaced adhesive to provide cup blanks having the adhesive arranged along one of their respective edge portions.

Another object of the invention is to provide a machine wherein novel means are employed for retaining the adhesive on the strip and blanks out of engagement with the strip and blank handling elements of the machine.

Another object of the invention is to provide a completely automatic machine for feeding a strip of cup material, applying adhesive thereto, cutting the strip into cup blanks, forming the blanks into cups and discharging the finished cups from the machine, the operating mechanism of the machine being so arranged as to contribute materially to the accuracy, speed and efficiency with which cups of the character described may be produced.

A further object of the invention is to provide a cup making machine of simple construction,

efficient in its operation and capable of extremely high speed in the production of cups.

A still further object of the invention is to improve machines of the character described in sundry details hereinafter referred to and particularly pointed out in the appended claims.

One embodiment of the present invention is shown for illustrative purposes in the accompanying drawings, in which:

10 Fig. 1 is a plan view of a cup forming machine embodying features of the present invention;

Fig. 2 is a sectional elevational view taken substantially as indicated by the line 2—2 of Fig. 1;

15 Fig. 3 is a fragmentary side elevational view of a portion of the machine taken as indicated and substantially within the limits indicated by the line 3—3 of Fig. 1;

Fig. 4 is an elevational view taken as indicated and substantially within the limits indicated by the line 4—4 of Fig. 1;

20 Fig. 5 is an enlarged sectional elevational view of the cup forming mandrel and presser roll structures, and of the mountings therefor, taken substantially as indicated by the line 5—5 of Fig. 1;

Fig. 6 is an end elevational view of the blank cutting mechanism and taken substantially as indicated by the line 6—6 of Fig. 2;

25 Fig. 7 is a fragmentary elevational view similar to a portion of Fig. 6 illustrating the manner of assembling certain of the blank cutting elements.

Figs. 8 and 9 are perspective views, respectively, of the upper and lower blank cutting dies;

30 Fig. 10 is a perspective view of a stripper adapted to be operatively related to the upper or movable cutting die illustrated in Fig. 8;

Fig. 11 is a fragmentary sectional view through a portion of the presser roll mounting and taken substantially as indicated by the line 11—11 of Fig. 5;

Fig. 12 is an enlarged elevational view of a valve and associated operating mechanism for controlling air under pressure employed for discharging the cups from the cup forming mandrel, the view being taken substantially as indicated by the line 12—12 of Fig. 1.

35 Fig. 13 is an enlarged sectional elevational view through a valve, similar to the one shown in Fig. 12, and related operating mechanism for controlling a suction, or air at less than atmospheric pressure, employed in connection with the cup forming mandrel for securing a cup blank thereto, the section being taken substantially as indicated by the line 13—13 of Fig. 1;

Figs. 14, 15 and 16 are semi-diagrammatic illustrating a series of successive steps in the cutting of a cup blank and the formation of a cup therefrom;

Fig. 17 is a plan view illustrating, on a relatively small scale, a cup blank employed in the formation of a cup by the steps illustrated in Figs. 14 to 16, inclusive; and

Fig. 18 is a perspective view illustrating a finished cup as formed and completed in a machine 10 of the character illustrated.

Referring to the drawings, the illustrative embodiment of the present invention shown therein comprises, generally, a frame 21 (Fig. 2) having glue or adhesive applying means 22 mounted thereon adjacent one end of the frame, blank cutting means indicated as a whole by the numeral 23 located preferably adjacent the opposite end portion of the frame and operatively related to a cup forming roll or mandrel 24 shown, in the present instance, as of cone-shaped form and a presser roll 25, also of cone-shaped form, operatively related thereto in a manner to receive a cup blank indicated at B cut from a strip of cup material A by the cutting means 23, and operable to form a cup on the mandrel 24.

As illustrated in Fig. 1, the cup material A may be supplied to the machine from a roll C mounted at one end of the frame 21 and the strip A drawn therefrom around a plurality of guide rollers 26, 27 and 28 by a plurality of pairs of feed rollers 29-31 and 32-33, the said feed rollers being adapted to be driven by a main drive shaft 34 rotatably mounted in the frame 21, the shaft 34 being provided with a pinion 35 (Fig. 3) operatively related to a pinion 36 for driving the feed roller 32, while the feed roller 31 is operatively connected to the drive shaft 34 by means of a chain 37 (Figs. 1 and 2), and the feed roller 29 is driven by a pair of gears 38 and 39 (Fig. 3) operatively connected, respectively, to the feed rollers 31 and 29.

It will be observed by reference to Figs. 1, 2 and 3 that a glue pot or receptacle 41 adapted to contain glue or other suitable adhesive is mounted adjacent the strip receiving end of the machine and is provided with a pick-up roller indicated, as a whole, by the numeral 42 having oppositely disposed cut away portions as indicated at 43 to provide annularly spaced contact surfaces 44 adapted to engage annularly spaced cooperating surfaces 45 formed on an adhesive applying roller 46 for transferring the adhesive thereto, the roller 46 being operative to apply the adhesive thereon to the strip A at spaced intervals adjacent a longitudinal edge thereof as shown at 47 in Figs. 1 and 14 to 17, inclusive.

For driving the pick-up roller 42 and the adhesive applying roller 46, a chain 48 (Figs. 1 and 2) operatively related to the feed roller 31 is connected to a stub shaft 49 rotatably mounted in the frame 21, and the pick-up or wiping roller 42 is operatively connected to the stub shaft 49 through a plurality of gears indicated at 51, 52 and 53 (Fig. 2). The adhesive applying roller 46 is operatively connected to the roller 42 by a pair of pinions 54 and 55 (Fig. 1), the latter being operatively connected to the roller 46 and mounted on a swinging frame 56 which may be secured to a portion of the frame 21 by means of a spring actuated pin 57 for retaining the roller 46 in operative position with respect to the strip of cup material A in its passage through the machine.

It will be noted by reference to Fig. 1 that the upper strip feeding rollers 29 and 32 are provided at their ends adjacent the adhesive 47 with portions 58 of reduced diameter to permit the adhesive 47 to pass beneath the rollers without engagement therewith.

The blank cutting mechanism indicated, as a whole, by the numeral 23 comprises an upper cutting die or cutter 59 having a knife edge portion 61 adapted to engage the strip A at a point between the spaced adhesive 47 and cooperable with a lower die 62 mounted in the frame 21 for severing the strip to form a cup blank of the form and character clearly shown in Figs. 14 and 17.

The upper cutting die 59 is mounted on the underside of a spacer 63 secured to a head 64 vertically movable in ways 65 mounted on the frame 21, and is normally retained in raised position by springs 66 (Figs. 3 and 6). For moving the head 64 and cutting die 59 downwardly in a manner to sever the strip A into cup blanks B, a rock shaft 67 is rotatably mounted in brackets 68 carried by the frame 21 and provided adjacent its central portion with an arm 69 having an adjustable stud 71 mounted adjacent its free end and engageable with the upper end portion of the head 64, while the outer ends of the rock shaft 67 are provided with arms 72 having anti-friction rollers 73 mounted thereon, respectively, adapted for engagement with a pair of cams 75 secured to the main drive shaft 34 and operable to rock the shaft 67 in a manner to move the head 64 and cutting die 59 carried thereby in a downward direction against the action of the springs 66 and in a manner to sever a cup blank B from the strip A at a point between the spaced adhesive 47 thereon.

As illustrated in Figs. 2, 3 and 10, the upper cutting die 59 is provided with a yieldably mounted stripper 75 to insure proper functioning of the cutter in relation to the strip A of cup material as it is fed through the machine, and it will be noted by reference to Fig. 10 that the stripper 75 is provided with a recess 76 in its lower edge portion adjacent one end thereof to permit the adhesive 47 on the strip A to pass beneath the stripper 75 without coming in contact therewith.

Slightly in advance of or substantially simultaneously with the severing of a blank B from the strip A of cup material by the cutter 59, the leading edge portion 77 (Figs. 14, 15 and 17) of the blank B is engaged between the rotatable cup forming mandrel 24 and the rotating presser roll 25 operating to press the cup blank firmly against the mandrel 24 during the formation of a cup thereon.

For rotating the mandrel 24 in proper relation with respect to the strip material feeding and blank cutting mechanism, the mandrel 24 is mounted on one end of a hollow shaft 78 rotatable on the frame 21 in bearings 78a and having a sprocket 79 secured to the shaft 78 and a chain 81 (Figs. 1 and 2) trained around the sprocket 79 and a sprocket 82 on a stub shaft 83 rotatably mounted in a bearing 84 mounted on the frame 21, the shaft 83 being operatively connected through a universal connection 85 with a shaft 86 also rotatably mounted on the frame 21 and having a pinion 87 secured to its outer end and adapted to mesh with a cooperating pinion 88 mounted on one end of the shaft 89 rotatably mounted on the frame 21 and having a sprocket 94 secured to its opposite end portion and

adapted to receive a chain 92 driven by a relatively larger sprocket 93 mounted on the main drive shaft 34, thereby providing a driving connection between the shaft 34 and mandrel 24 to produce proper speed ratios for insuring the operation and rotation of the mandrel 24 in proper relation with respect to the feeding of the strip A and the severing of the blanks B therefrom.

Mounted also on the hollow shaft 78 is a bevel pinion 94 operatively related to a bevel pinion 95 secured to an axially movable shaft 96 rotatably mounted in bearings 97 and 98 on the frame 21, and to which the presser roll 25 is connected for rotating the presser roll in proper relation with respect to the mandrel 24.

For releasably securing the leading edge portion 71 of a blank B to the mandrel 24 during the rotation thereof and the forming of a cup thereon, the mandrel 24 is provided with a sucker opening 99 (Figs. 5, 14 and 15) communicating with one end of an elongated opening or passage 101 formed in and shown, in the present instance, as extending axially of the hollow shaft 78, the opposite end of the passage 101 communicating with a T-fitting 102 having a suction pipe 103 connected thereto, the said suction pipe being adapted to communicate through a pipe 104 with suitable suction producing means (not shown) as, for example, a vacuum pump or the like, for producing at the sucker opening 99 of the mandrel 24, a suction for securing the leading edge portion 71 of a blank B to the mandrel during the rotation thereof and the forming of a cup thereon.

For controlling the suction in the passage 101 and sucker opening 99 in proper relation with respect to the movements of the cup material strip A and cup blanks B through the machine, a valve indicated, as a whole, by the numeral 105 (Figs. 1, 4 and 13) is positioned between the suction pipes 103 and 104 and comprises a housing 106 having a chamber 107 formed therein and provided with a valve seat 108 adapted to be engaged by a valve member 109 for controlling the passage of air through the housing 106 from the intake side thereof adjacent the pipe 103 to the outlet or vacuum side of the housing adjacent the pipe 104. For controlling the position of the valve member 109 and the operation of the valve 105 in proper relation with respect to the movements of the cup material and the formation of a cup therefrom, a lever 111 is pivotally mounted on a fixed stud or shaft 112 and provided adjacent one of its ends with a lifter arm 113 adapted to engage a stem 114 connected with the valve member 109, the opposite end of the lever 111 having a roller 115 mounted thereon adapted to be engaged by a cam 116 secured to the main drive shaft 34, the cam 116 being provided with a lobe 117 of substantial dimensions for lifting and retaining the valve member 109 away from or out of engagement with the seat 108 for a substantial length of time to enable the suction at the sucker opening 99 of the mandrel 24 to operate upon the leading edge portion 71 of a cup blank B during formation of a cup, the lower side or dwell of the cam 116 permitting the spring 118 of the valve 105 to close the valve after the formation of the cup is completed to permit its discharge from the mandrel 24.

For controlling the operation of the presser roll 25 to engage a cup blank B during the formation of a cup on the mandrel 24 and for releasing the cup to be discharged therefrom when completed, the presser roll 25 and shaft 96 are ro-

tatable with the bevel pinion 95 and longitudinally or axially movable with respect thereto and to the bearings 97 and 98 by reason of a sliding connection between a key or spline 119 on the shaft 96 and the bevelled pinion 95. The shaft 96 is provided with a shoulder 121 adapted to be engaged by one side of a collar 122, the opposite side of the collar being engaged by a spring 123 operating between the collar 122 and a collar 124 secured against endwise movement on the shaft 96 by the bearing 98, the spring 123 acting to yieldingly urge the presser roll in an axial direction and at an angle to the axis of rotation of the mandrel 24 in a manner to yieldingly engage a cup blank B secured to the mandrel, and to suitably and yieldingly press the blank against the mandrel during the formation of a cup thereon.

For moving the presser roll 25 and shaft 96 in the opposite direction away from the mandrel 24 to permit the discharge of a finished cup therefrom, the outer or opposite end of the shaft 96 is provided with an annularly grooved collar 125 adapted to receive the inwardly extending trunnions 126 of a shipper fork 127 secured to one end of a rock shaft 128 rotatably mounted in a bearing 129 (Fig. 4) carried by the frame 21. Secured to the opposite end of the rock shaft 128 is an arm 131 connected at its upper end to one end of a link 132 (Figs. 1 and 4) having its opposite end portion pivotally connected at 133 to one end portion of a lever 134 shown, in the present instance, as pivotally mounted intermediate its ends at 135 on the frame 21, the opposite end portion of the lever 134 being provided with an anti-friction roller 136 adapted to be engaged by a cam 137 secured to the main drive shaft 34 and operative to rock the arm 134 about its pivot 135 and the rock shaft 128 in its bearing 129 in a manner to move the presser roll 25 and shaft 96 axially in the bearings 97 and 98 against the action of the spring 123 in a manner to release a finished or completed cup formed on the mandrel 24.

For discharging a completed cup from the mandrel 24, the mandrel is provided, preferably, with a plurality of blow-off ports 138 (Figs. 1, 2, 5, 14 and 15) extending outwardly through portions of the mandrel to the outer surface thereof and communicating at their inner ends with one end of a tubular member 139 (Fig. 5) positioned axially within the hollow shaft 78 and in spaced relation with respect to the walls of the suction passage 101 formed therein, the opposite end of the tubular member 139 being rotatably mounted in a fitting 141 secured at its inner end to the T-fitting 102 and having an elbow 142 secured to its outer end connected to an air pressure pipe 143 communicating through a pipe 144 with a source of air pressure supply (not shown) as, for example, an air compressor or the like.

For controlling the air pressure in the tubular member 139 and at the blow-off ports 138 formed in the mandrel 24 for discharging a completed cup therefrom, a valve indicated, as a whole, by the numeral 145 and of a construction substantially like that shown in Fig. 13 and described with reference to the suction control means, is positioned between the pressure pipes or conductors 143 and 144 and is provided with a valve stem 146 extending outwardly and downwardly from the housing 147 of the valve.

For controlling the operation of the valve 145 and the pressure at the blow-off ports 138 of the mandrel 24 in proper relation to the feeding of

the cup material to the mandrel 24 and the formation of a completed cup thereon, a valve actuating lever 148 is pivotally mounted at 149 on a bracket 151 carried by the frame 21 and is provided with an end portion 152 engageable with the valve stem 146, and having its opposite end portion 153 provided with an anti-friction roller 154 adapted to be engaged by a cam 155 secured to the main drive shaft 34, the cam 155 having a lobe 156 thereon for depressing the end portion 153 of the lever 148 and elevating the end portion 152 engageable with the valve stem 146 for opening the valve to permit a charge of compressed air at the blow-off ports 138 for discharging a completed cup from the mandrel 24 when the presser roll 25 has been withdrawn from engagement therewith.

For trimming the open end portion or edge 151 of a cup 158 (Fig. 18) along a line indicated at D (Fig. 17) a rotary cutting disc or knife 159 (Figs. 1, 2 and 16) is secured to one end of a shaft 161 rotatably mounted in a bearing 162 formed integrally with one of the bearings 78a in which the hollow shaft 78 is mounted, and secured to the opposite end of the shaft 61 is a pinion 163 operatively related to a pinion 164 secured to the shaft 78 in a manner to be driven thereby.

Referring to Figs. 2 and 14 to 18, inclusive, of the drawings, it will be noted particularly by reference to Fig. 14 that the strip A of cup material is projected in the direction of the arrow E beyond the cutting edge 61, indicated at F, of the die 59 until the leading edge portion 77 of the strip is positioned between the mandrel 24 and presser roll 25 where the said leading edge portion is releasably secured to the mandrel 24 by suction at the sucker opening 99. Substantially at the same time or immediately thereafter, the strip A is severed along the line F and between the adhesive 47 by the cutting edge 61 of the cutter 59 (Figs. 2 and 14) in a manner to form a cup blank B having a forwardly projecting tab 165 formed thereon, thereafter, by reason of the rotation of the mandrel 24, the blank B is drawn from the cutter as shown in Fig. 15 and wrapped around the mandrel 24 to form a cone-shaped cup, and as the wrapping of the blank continues and the formation of the cup progresses, the adhesive 47, by reason of the action of the presser roll 25, is pressed firmly and securely against a portion of the outer side of the blank to secure the edge portion adjacent the adhesive thereto, and as the formation of the cup further progresses, the adhesive will be squeezed outwardly onto the tab 165 in a manner to secure the tab to the outer side of the finished cup, as shown in Fig. 18, whereupon the suction at the sucker opening 99 is discontinued and air under pressure permitted to enter the tubular member 139 and blow-off ports 138 to discharge the finished cup from the mandrel, it being understood that during the rotation of the mandrel and the formation of the cup thereon, the edge portion 151 of the cup 158 will have been trimmed as indicated by the dotted line D (Fig. 17) by the cutting knife or disc 159.

It will be understood also that after severing the strip A along the line F to form a cup blank B that the edge of the strip A adjacent the cutter then becomes a leading edge portion as indicated at 77a in Fig. 15, and as the strip is moved forwardly toward the mandrel 24, the portion indicated by the dot and dash line 77b (Fig. 14) will be positioned adjacent the cutting edge 61 of the

cutter 59 and there severed to form a subsequent or following blank indicated at B'.

For retaining the adhesive 47 on the blank B out of engagement with the cutter 59, as it is drawn therefrom by the rotation of the mandrel 24, the cutting disc 59 is provided on its underside with a deflector 166 (Figs. 6, 7 and 8) positioned laterally and to the outer side of the adhesive 47 as it passes beneath the cutting die 59.

If desired, a pair of guide plates 167 and 168 (Figs. 1, 2 and 14) may be positioned above and below the strip A adjacent one of its longitudinal edge portions for guiding the projecting end of the strip between the mandrel 24 and presser roll 25.

For driving the main shaft 34, a sprocket 169, for example, (Fig. 1) may be secured to one end of the shaft and connected by means of a chain 171 to a suitable source of power (not shown) such, for example, as an electric motor or the like, by which, through suitable driving connections, the entire mechanism of the cup making machine may be operated.

From the foregoing description, it will be noted that the operation of the machine is substantially as follows:

Assuming that power has been applied to the drive shaft 34, the strip of cup material A is drawn from the supply roll C through the machine by the feed rollers 29-31 and 32-33 and past the adhesive applying roller 46 by which an adhesive is applied to the strip A at spaced intervals along one edge thereof as illustrated in Figs. 1 and 14. The strip A in its continued movement is projected by the feed rolls between upper and lower cutting dies 59 and 62, respectively, to position the leading edge portion 77 of the strip between the cup forming mandrel 24 and presser roll 25 adjacent the sucker opening 99 of the mandrel. The said leading edge portion 77 of the strip is then releasably secured to the mandrel by suction through the operation of the cam 116 to open the suction valve 105, and at approximately the same time, through the operation of the cam 137, the presser roll 25 is moved into engagement with the edge portion of the strip by the spring 123 and the strip severed by the cutting edge 61 of the die 59 through the operation of the cams 74 acting through the arms 72, rock shaft 61 and arm 69 to force the head 64 and cutting die 59 mounted thereon downwardly as illustrated in Fig. 2, whereupon the rotation of the mandrel 24 and presser roll 25 act to draw the blank B, formed by the cutting of the strip, away from the cutting mechanism and wrap the blank around the mandrel 24 into cup form, during which operation the cutting disc or knife 159 acts to trim the edge of the cup and the presser roll serves to press the adhesive 47 against the outer sides of the cup and onto the tab 165 of the blank for securing the edge portion thereof adjacent the adhesive and the tab 165 to the sides of the finished cup as illustrated in Fig. 18.

Upon completion of the cup 158, the cam 137 again acts through its connection with the shaft 96 to move the presser roll 25 in an axial direction out of engagement with the finished cup, whereupon, through the operation of the cam 156, the blow-off valve 147 is opened to permit air under pressure to pass through the tubular member 139 and blow-off ports 138 formed in the mandrel 24 for discharging the finished cup therefrom, immediately following which, the

formation of a subsequent cup in the manner above described is repeated.

It will be observed from the foregoing description that the present invention provides a novel construction and arrangement in continuously operating rotary cup forming machines wherein the cup blanks are cut from a continuous strip of cup material fed continuously to the machine, and wherein the construction and arrangement of elements embodying the present invention provides an efficient machine capable of extremely high speed in the production of cups of the character described.

What I claim as new and desire to secure by Letters Patent is:

1. In a cup forming machine, means for feeding a strip of cup material therethrough, an adhesive applying roller engageable with one side of said strip, cutting dies for cutting said strip into cup blanks, a rotatable cup forming mandrel having a sucker opening therein communicating with a suction passage co-axial with the axis of rotation of said mandrel for securing the leading edge portion of a blank thereto, a rotatable presser roll axially movable in one direction to engage a blank on said mandrel during the forming of a cup thereon and movable in the opposite direction to release the cup when completed, said mandrel having a tip end portion formed integrally therewith and having blow-off ports formed therein communicating with an air pressure supply passage coaxial with the axis of rotation of said mandrel for discharging a completed cup therefrom, and means for controlling the suction and pressure in said passages.

2. In a cup forming machine, a main drive shaft, means driven by said shaft for feeding a strip of cup material through the machine, an adhesive applying roller operatively related to said shaft to be driven thereby and having peripherally spaced contact surfaces engageable with said material for applying adhesive thereto at spaced intervals, a cutting die actuated by the rotation of said shaft and engageable with said strip between the spaced adhesive thereon for cutting the strip into cup blanks, a rotatable cone-shaped cup forming mandrel operatively related to said shaft and having a sucker opening communicating with a suction passage co-axial with the axis of rotation of said mandrel for securing the leading edge portion of a blank thereto, a rotatable cone-shaped presser roll having an axis of rotation positioned at an angle to the axis of said mandrel, means operatively related to said presser roll and said shaft for moving the presser roll axially in one direction to engage a blank on said mandrel during the forming of a cup thereon and for moving the roll in the opposite direction to release the cup when completed, said mandrel having blow-off ports formed therein communicating with an air supply passage co-axial with the axis of rotation of said mandrel and within and separated from said suction passage for discharging a completed cup from said mandrel, a pair of valves operatively related, respectively, to said passages, and means on said shaft operatively related to said valves for controlling the suction and pressure in the respective passages in accordance with the forming and completion of a cup on said mandrel.

3. In a cup forming machine, a frame, a main drive shaft rotatably mounted therein, a plurality of pairs of cooperating feed rollers opera-

tively related to said shaft for feeding a strip of cup material through the machine, an adhesive applying roller having portions engageable with said strip for applying adhesive thereto at spaced intervals along an edge thereof, a cutting die engageable with said strip between the adhesive thereon for cutting the strip into cup blanks, means mounted on said frame and operatively related to said shaft for actuating said die, a rotatable cup forming mandrel and cooperating presser roll adapted to engage a cup blank cut from said strip and remove the blank from said die, certain of said feed rollers having a portion of reduced diameter adjacent the adhesive on said strip, and a deflector on said cutting die engageable with a portion of the cup blank for holding the adhesive thereon out of engagement with the die as the blank is drawn therefrom by said mandrel and presser roll.

4. In a cup forming machine, a frame, a hollow shaft rotatably mounted thereon, a cup forming mandrel on said shaft having a sucker opening formed in one side of the mandrel communicating with the interior of the shaft, said mandrel having a blow-off port extending outwardly through a portion thereof to the surface of the mandrel, a tubular member positioned in the interior of said hollow shaft axially thereof and in spaced relation thereto and extending longitudinally thereof, said tubular member communicating with a pressure conducting pipe and said blow-off port for conducting air under pressure to said port for discharging a finished cup from said mandrel.

5. In a cup forming machine, a frame, a hollow shaft rotatably mounted thereon, a cup forming mandrel mounted on said shaft and having a sucker opening formed in one side of the mandrel and a blow-off port extending outwardly through a portion of the mandrel to the surface thereof, and a tubular member positioned in the interior of said hollow shaft axially thereof and in spaced relation thereto and extending longitudinally thereof to provide a suction passage communicating with a suction pipe and said sucker opening, said tubular member communicating with a pressure conducting pipe and said blow-off port for conducting air under pressure to said port for discharging a finished cup from said mandrel.

6. In a cup forming machine, a frame, a shaft rotatably mounted thereon, said shaft having an elongated opening formed therein and extending axially thereof, a cup forming mandrel mounted on one end of said shaft and having a sucker opening formed in one side of the mandrel and a plurality of annularly spaced blow-off ports extending outwardly through a portion of the mandrel to the surface thereof, and a tubular member positioned axially in the elongated opening in said shaft and in spaced relation to the walls of said opening to provide a suction passage outside said member communicating at one of its ends with a suction pipe and at its opposite end with said sucker opening, said tubular member communicating at one of its ends with a pressure conducting pipe and at its opposite end with said blow-off ports for conducting air under pressure to said ports for discharging a finished cup from said mandrel.

7. In a cup forming machine, a frame, a main drive shaft rotatably mounted therein, a hollow shaft rotatably mounted on said frame, said hollow shaft having an elongated opening formed

therein and extending axially thereof, a cup forming cone-shaped mandrel mounted on one end of said hollow shaft and having a sucker opening formed in one side of the mandrel, said mandrel having a plurality of annularly shaped blow-off ports extending outwardly through a portion of the mandrel to the surface thereof, a tubular member positioned axially in the elongated opening in said hollow shaft and in spaced relation to the walls of said opening to provide a suction passage outside said tubular member communicating at one of its ends with a suction pipe and at its opposite end with said sucker opening, said tubular member communicating at one of its ends with a pressure conducting pipe and at its opposite end with said blow-off ports for conducting air under pressure thereto, a cone-shaped presser roll rotatably mounted on said frame and having an axis extending at an angle to the axis of said hollow shaft, said presser roll being axially movable to engage a cup blank adjacent said mandrel, means in said suction and pressure pipes, respectively, for controlling the suction at said sucker opening and the pressure at said blow-off ports, and means operatively related to said main drive shaft for actuating said valves.

8. In a machine for forming a cup from a blank of flexible material, a frame, a main drive shaft rotatably mounted therein, a hollow shaft rotatably mounted on said frame and operatively related to said drive shaft, said hollow shaft having an elongated opening therein and extending axially thereof, a cup forming cone-

5 shaped mandrel mounted on one end of said hollow shaft and having a sucker opening formed in one side of the mandrel, said mandrel having a plurality of annularly spaced blow-off ports extending outwardly through a portion of the mandrel to the surface thereof, a tubular member positioned axially in the elongated opening in said hollow shaft and in spaced relation to the walls of said opening to provide a suction passage in said hollow shaft outside said tubular member communicating at one of its ends with a suction pipe and at its opposite end with said sucker opening, said tubular member communicating at one of its ends with a pressure conducting pipe and at its opposite end with said blow-off ports for conducting air under pressure thereto, a cone-shaped presser roll having a driving connection with said hollow shaft and rotatably mounted on said frame about an axis extending at an angle to the axis of said hollow shaft, said presser roll being axially movable to engage a cup blank adjacent said mandrel, means for supplying cup blanks to said mandrel and presser roll to be engaged thereby, valves in said suction and pressure pipes, respectively, for controlling, respectively the suction at said sucker opening to secure the leading edge of a blank to said mandrel and for controlling the pressure at said blow-off ports to discharge a finished cup from the mandrel, and cams on said main drive shaft for actuating the respective valves.

HAROLD GREENHILL.
